DOOR KNOB STRUCTURE

Era M. Frappier, Clio, Mich.

Application August 7, 1936, Serial No. 94,857

1 Claim. (Cl. 292—351)

This invention appertains to new and useful improvements in door knob structures.

The principal object of the present invention is to provide a door knob structure wherein a knob can be firmly secured to its shaft in such a way that it cannot easily become disassociated, which frequently occurs, with the conventional types of door knob structures now on the market.

Other important objects and advantages of the invention will become apparent to the reader of the following specification.

In the drawing:—

Figure 1 represents a side elevational view of the structure mostly in longitudinal section.

Figure 2 is an end elevational view of the integral knob and shaft structure with the detachable knob removed.

Figure 3 is a cross section on line 3—3 of Figure 1.

Figure 4 is an end elevational view of the entire structure.

Figure 5 is an inside elevational view of the knob shown in Figure 4.

Figure 6 is a fragmentary side elevational view of the retaining screw.

Figure 7 is a section on line 7—7 of Figure 6.

Figure 8 is an edge elevational view of the spring washer.

Referring to the drawing wherein like numerals designate like parts, it can be seen that the numeral 5 represents the shaft which connects the knobs 6—7. The shaft 5 and the knob 6 are preferably integral and the knob 6 has the shoulder construction 8 which of course 35 abuts one side of a door (not shown).

The knob 7 is provided with the shank formation 9 and the recess 10 therein. The shaft 5 is provided with notches 11 at one end and at longitudinal spaced intervals so that the fitter can 40 gauge the length the shaft should be for different size doors and cut on these notches.

The notched end of the shaft 5 is provided with a threaded bore 12 for receiving the elongated screw 13 which is provided with a head 14 which can seat in the countersink 15 of the knob 7. It is preferable that a spring washer 16 be seated in a recess surrounding the screw 13 and engage into the circumferential groove 13a of the screw 13 so as to prevent the screw 13 from accidentally unscrewing from the shaft 5.

To place this split washer 16 in place, the washer is spiralled into the recess 15 of the knob 7. The opening in the washer is substantially smaller in diameter than the diameter of the screw 13. After the washer 16 has been disposed in the recess 15, the screw 13 is forced through the recess 15 and washer 16, the washer expanding as the screw 13 is forced through the same. When the groove 13a of the screw 13 reaches the washer 16, the washer will contract or spring into the groove and thus the screw 20 becomes swivelly connected to the knob.

While the foregoing specification sets forth the invention in specific terms, it is to be understood that numerous changes in the shape, size and materials may be resorted to without departing from the spirit and scope of the invention as claimed hereinafter.

Having thus described the invention what is claimed as new is:—

A door knob construction comprising a body 30 having a bore therethrough, a knob retaining screw for disposition in the bore, said knob having a recess therein surrounding the bore, a split washer disposed in the recess and having an opening therethrough substantially smaller in 35 diameter than the diameter of the screw, said screw having a circumferential groove therein for receiving the inner edge portion of the washer.
